UNITED STATES PATENT OFFICE

170,912

SANDWICH STEADIER

Robert C. Collins, Winnipeg, Manitoba, and
William Saunderson, Vancouver, British Columbia, Canada

Application July 21, 1952, Serial No. 20,698

Term of patent 7 years

(Cl. D44—29)

To all whom it may concern:

Be it known that we, Robert C. Collins and William Saunderson, citizens of Canada and residents of the city of Winnipeg, Province of Manitoba, Dominion of Canada, and the city of Vancouver, Province of British Columbia, Dominion of Canada, respectively, have invented a new, original, and ornamental Design for a Sandwich Steadier, of which the following is a specification, reference being had to the accompanying drawings, forming part thereof. Figure 1 is a perspective view of a sandwich steadier, embodying our new design, and Figure 2 is a plan view thereof.

We claim:

The ornamental design for a sandwich steadier, as shown.

ROBERT C. COLLINS.
WILLIAM SAUNDERSON.
